CLAIM

The ornamental design for a toy weapon, as shown and
described.

DESCRIPTION

FIG. 1 is a side elevational view of a toy weapon showing
my new design, the side opposite being a mirror
image;

FIG. 2 is top plan view thereof;

FIG. 3 is a bottom plan view thereof;

FIG. 4 is a rear elevational view thereof;

FIG. 5 is a front elevational view thereof;

FIG. 6 is side elevational view of a modified embodiment
of the design shown in FIGS. 1-5, the side opposite
being a mirror image;

FIG. 7 is a top plan view thereof;

FIG. 8 is a bottom plan view thereof;

FIG. 9 is a rear elevational view thereof;

FIG. 10 is a front elevational view thereof; and,

FIG. 11 is a perspective view of the design shown in
FIGS. 1-5.
